UNITED STATES PATENT OFFICE.

ARTHUR A. JOHNSON, OF WASHINGTON, DISTRICT OF COLUMBIA, ASSIGNOR TO
UNDERWOOD TYPEWRITER COMPANY, OF NEW YORK, N. Y., A CORPORATION
OF DELAWARE.

TYPEWRITING MACHINE.

1,421,946.

Specification of Letters Patent. Patented July 4, 1922.

Application filed July 6, 1921. Serial No. 482,694.

To all whom it may concern:

Be it known that I, ARTHUR A. JOHNSON, a citizen of the United States, residing in Washington, District of Columbia, have invented certain new and useful Improvements in Typewriting Machines, of which the following is a specification.

This invention relates to typewriting machines of the class shown in the patent to 10 Wernery & Smith, No. 1,132,055, dated March 16, 1915, in which a longitudinally folded web is led around a revoluble platen of a typewriting machine, the latter having provisions for carrying carbons between the 15 plies of the web and for shifting the carbons back to fresh portions of the web as the typing proceeds, the web usually comprising a succession of printed forms, each of which is torn off as soon as typed.

20 Heretofore, it has been proposed to use, instead of a folded web, separate plies to be drawn from spools mounted below and at the rear of the extension of the carriage on which is mounted the usual carbon-carrier 25 for controlling the carbon-sheets. In using separate plies or webs in these machines difficulty was experienced in drawing the plies from the spools in the operation of line-feeding the plies around the platen and in maintaining the superposed forms in alignment. 30 To overcome these difficulties, provision was made of clamping means on the carrier adapted for use in pulling off webs or plies from the spools to produce slack, and for 35 clamping the webs during the feeding thereof around the platen to prevent or minimize the creeping of the plies.

The main object of the present invention is to provide improved means to control the 40 feeding of separate webs or plies around the platen.

In carrying out the invention, provision may be made of pins or the like mounted on the carbon-carrier in position to enter perforations in the superposed plies, said perforations being arranged in rows longitudinally of the plies and preferably spaced at distances corresponding to the lengths of the successive forms. Preferably, the perforations are in two rows, one near each edge of 45 each ply, and use is made of two pins mounted on the carbon-carrier at the rear of the carbon-sheets so as to avoid interference therewith. To insure entrance of the pins

into the perforations when the pins and 55 perforations are brought into proper relation, suitable means, such as springs, may be provided to urge the pins into the perforations.

In order to withdraw the pins from the 60 perforations, provision is made of means controlled by a finger-piece on the usual carbon-carrier handle for lifting said pins simultaneously to ineffective position. Preferably, such lifting means is normally urged to operate by suitable urging means, such as a spring. To render the pin-lifting means ineffective, provision is made of a 65 finger-piece upon the carbon-carrier suitably connected to the lifting means, and also of a 70 latching device which will normally prevent lifting of the pins by said lifting means. In order to render said latching device ineffective, provision may be made for automatically shifting the same to ineffective position 75 upon movement of the carbon-carrier to its forward limiting position.

When the pins rest in perforations in the superposed plies, the plies may be fed around the platen and typing effected thereon. 80 Upon completion of the last entry on a set of superposed forms, the platen may be thrown up in the usual manner to enable straightening of the plies and the carbon-carrier advanced sufficiently to render the 85 latch ineffective. Inasmuch as superposed plies have been maintained in proper relative position where engaged by the pins, the straightening of the plies will effect a realignment of the forwardly-extending forms, 90 and, upon movement of the carbon-carrier to the rear, the pins, which have again been released by operation of the finger-piece, may enter the next set of perforations. The pins may be released after returning the carrier 95 to its rearward position, or before the carrier has reached such position, being supported in the latter case by the upper ply until they are brought into register with the perforations. It should be understood that the 100 typed forms are severed in the usual manner before advancing the next set of forms for typing.

The plies may then be advanced around the platen for printing on the next set of 105 superposed forms, the plies having been drawn from the spools or other supply means to form slack, if such action is desired.

Other features and advantages will hereinafter appear.

In the accompanying drawings,

Figure 1 is a side elevation, partly in section, showing the invention applied to so much of the carriage of an Underwood type-writing machine of the fan-fold type as is necessary for the purpose of illustration, the mechanism being shown in position to begin 10 typing on a set of superposed forms.

Figure 2 is a plan view, showing the parts in the same position as in Figure 1.

Figure 3 is a view similar to Figure 1, but showing the platen lifted and the registering 15 pins in raised position.

Figure 4 is a view similar to Figure 3, but showing the carbon-carrier at an intermediate position in its return movement, the pins having been released so that they will 20 be sustained by the upper ply until brought into register with the perforations in the superposed plies.

A platen 1 is supported on an axle 2 journaled in the ends 3 of a lifting frame 4 25 which includes a front paper-table 5. The ends of the lifting frame are pivotally mounted on a rod 6, extending from one end to the other of a typewriter carriage 7, the ends 3 of the lifting frame being provided 30 with arms 8, which, when the platen is in its normal position, will rest on a rod 9 supported by the carriage. The platen is then in position to co-operate with a rear paper-table 10 and rear and front feed-rolls 11 and 35 12, respectively, in feeding work around the platen.

Connected with the typewriter carriage 7 is a rearward extension, comprising front and rear rods 13 and 14, respectively, connected by rails 15, on which a carbon-carrier 16 is mounted for movement toward and from the platen. The carbon-carrier may be provided with blades 17, from which extend carbon-sheets, and an arm 18 extending 40 toward the front of the machine to facilitate shifting of the carriage by the operator, the arm 18 preferably being bent at right angles near its end to form a finger-piece 19. Provision is also made of stops 45 20 and 21 to limit the movement of the carbon-carrier in a rearward or forward direction, respectively. The stops may be secured in adjusted position by means of suitable set-screws 20^a and 21^a, respectively.

50 The separate plies or webs 22 are led from any suitable source of supply over the rod 14 at the rear of the machine, and are arranged with respect to the blades 17, so that carbon-sheets 23, secured to the blades, 55 will be interleaved between the plies; the forward ends of the carbon-sheets and webs being passed beneath the platen in raised position, as shown in Figure 3, and over a knife 24 supported by the ends 3 of the lifting frame. The platen is then swung down 60

to normal position, as shown in Figure 1, and typing is effected on the webs or plies by means of types 25 on type-bars 26.

According to the present invention, provision is made of means to prevent relative 70 displacement between corresponding superposed forms on the different plies, due to the tendency of the plies to creep when fed around the platen. To this end, provision is made of perforations in the plies, so positioned that, when a set of superposed forms is in position to begin typing thereon, as shown in Figure 1, pins 28 mounted at the rear of the carbon-carrier may pass into said 75 perforations, thereby preventing displacement of the various webs where engaged by the pins. Preferably, the pins 28 are mounted for vertical sliding movement in brackets 29 supported on the sides of the carbon-carrier, and are normally urged downwardly 80 by springs 30 having forked ends engaging grooves in the upper ends of the pins. When the pins 28 are in their lowest positions, as shown in Figure 1, their lower ends extend into perforations in a support 31 on which 90 the plies rest. The support 31 is here shown as a channel plate concave downwardly and having a flange 32 by which it may be fastened to the carbon-carrier 16 in any suitable manner, as by screws 32^a. 95

In order to lift the pins 28 from effective position, provision may be made of a rock-shaft 33 supported on the carbon-carrier 16 at the rear of the pins and having secured thereto suitable arms 34, preferably in the 100 form of leaf-springs and extending beneath pins 35 projecting from the pins 28. The arms 34 may be secured to the shaft 33 by any suitable means, such as screws 36. At the end of the shaft 33, near the arm 18 of the carbon-carrier, a downwardly-extending arm 37 is fixed thereon, and the shaft is urged to rotate in a counter-clockwise direction by means of a leaf-spring 38 secured at one end to the arm 18 and at the other end 110 to said arm 37, thereby tending to lift the pins 28 to ineffective position. The connection between the spring 38 and the arm 37 may be effected in any suitable manner, as, for example, by inserting the end of spring 115 38 in a slot formed in the arm 37. To rock the shaft 33 in clockwise direction to permit pins 28 to descend, provision is made of a link 39 pivoted at its rear end to the lower end of arm 37 and at its forward end to the 120 lower end of a lever 40, pivoted at 41 on arm 18 and provided with a finger-piece 42 at its upper end, so that, upon pressing finger-piece 42 toward finger-piece 19 by grasping the same between the thumb and finger, the 125 shaft 33 will be rocked to the Figure 1 position.

In order that the arms 34 may remain in depressed position, provision is made of a latch-lever 44 pivoted at 45 on arm 18 and 130

urged upwardly by a spring 46, so that, when the arm 37 is in its Figure 1 position, the rear end of the lever will be moved into the path of arm 37 to prevent its movement 5 in a counter-clockwise direction, the movement of the lever 44 under the influence of spring 46 being limited by means of a pin 47 projecting from arm 18. When the typing is completed on one set of superposed 10 forms, the carbon-carrier will be in an advanced position, and it will be necessary to release the same from the superposed plies and return it to the left, as shown in Figure 1, so as to permit the pins 28 to enter 15 another set of perforations in the plies. To this end, the forward end of lever 44 is provided with a laterally-extending cam-member 48, which, upon the advance of the carbon-carrier to the limit of its forward movement, 20 will engage the rearward end of a screw 49, threaded into the stop 21, and ride upwardly thereon, thereby rocking the lever 44 and releasing the arm 37 to the influence of the spring 38. The pins 28 will then be 25 lifted to Figure 3 position. It will be evident that, by adjusting the position of the screw 49, the release of the arm 37 may be varied without shifting the stop 21.

The carbon-carrier may then be shifted to 30 the rear, as shown in Figure 3, and the pins 28 released by actuation of the finger-piece 42, thereby causing the pins 28 to co-operate with the superposed plies 22, as shown in Figure 1. If desired, the finger-piece 42 35 may be actuated before the carbon-carrier is restored to its original position, and the pins 28 will then ride on the surfaces of the upper ply and drop into the Figure 1 position when the carrier reaches the rearward limit 40 of its movement.

It will be evident that the pins 28 not only serve to maintain the superposed plies against relative movement during the forward movement of the carbon-carrier, but 45 also serve to assure proper alignment or register between the forms on the superposed plies.

An important feature of this invention is the provision of means whereby the extent 50 of feed of the web is controlled without the usual leading-edge gage. Another important feature is that the webs are not intercepted in their movements by the pins. The paper and pins are relatively stationary when engagement is effected.

Variations may be resorted to within the scope of the invention, and portions of the improvements may be used without others.

Having thus described my invention, I 60 claim:

1. In a typewriting machine, in combination, a revolute platen, a carriage therefor having a rearward extension, a carbon-carrier mounted for forward and rearward 65 movement on said extension, and means to

prevent cumulative creeping of separate plies fed around said platen, comprising pins mounted on said carrier, so that they may be projected into correspondingly positioned perforations in superposed forms on the separate plies, and thereby prevent relative displacement of the forms to the rear of said pins during the feeding of the forms in advance of said pins around the platen. 70

2. In a typewriting machine, in combination, a revolute platen, a carriage therefor having a rearward extension, a carbon-carrier mounted for forward and rearward movement on said extension, and means to prevent cumulative creeping of separate plies fed around said platen, comprising pins mounted on said carrier, so that they may be projected into correspondingly positioned perforations in superposed forms on the separate plies, and thereby prevent relative 80 displacement of the forms to the rear of said pins during the feeding of the forms in advance of said pins around the platen, and means for withdrawing said pins simultaneously. 90

3. In a typewriting machine, in combination, a revolute platen, a carriage therefor having a rearward extension, a carbon-carrier mounted for forward and rearward movement on said extension, and means to prevent cumulative creeping of separate plies fed around said platen, comprising pins mounted on said carrier, so that they may be projected into correspondingly positioned perforations in superposed forms on the separate plies, and thereby prevent relative 95 displacement of the forms to the rear of said pins during the feeding of the forms in advance of said pins around the platen, means for withdrawing said pins simultaneously, 100 and means normally urging said withdrawing means to effective position. 105

4. In a typewriting machine, in combination, a revolute platen, a carriage therefor having a rearward extension, a carbon-carrier mounted for forward and rearward movement on said extension, and means to prevent cumulative creeping of separate plies fed around said platen, comprising pins mounted on said carrier, so that they may be 110 projected into correspondingly positioned perforations in superposed forms on the separate plies, and thereby prevent relative displacement of the forms to the rear of said pins during the feeding of the forms in advance of said pins around the platen, means for withdrawing said pins simultaneously, 115 and means normally urging said withdrawing means to effective position, and a latching device to maintain said withdrawing means in 120 ineffective position. 125

5. In a typewriting machine, in combination, a revolute platen, a carriage therefor having a rearward extension, a carbon-carrier mounted for forward and rearward 130

- movement on said extension, and means to prevent cumulative creeping of separate plies fed around said platen, comprising pins mounted on said carrier, so that they 5 may be projected into correspondingly positioned perforations in superposed forms on the separate plies, and thereby prevent relative displacement of the forms to the rear of said pins during the feeding of the 10 forms in advance of said pins around the platen, means for withdrawing said pins simultaneously, means normally urging said withdrawing means to effective position, a latching device to maintain said withdrawing 15 means in ineffective position, and means whereby advance of said carrier to a predetermined position will cause said latching device to be rendered ineffective. 6. In a typewriting machine, in combination, a revolute platen, a carriage therefor having a rearward extension, a carbon-carrier mounted for forward and rearward movement on said extension, and means to prevent cumulative creeping of separate plies 20 fed around said platen, comprising pins mounted on said carrier, so that they may be projected into correspondingly positioned perforations in superposed forms on the separate plies to prevent relative displacement of the forms during the feeding of the plies around the platen, means for withdrawing said pins simultaneously, comprising a projection on each of the pins, a 25 shaft, arms projecting from said shaft and underlying said projections and means to urge said shaft to turn in a direction to withdraw said pins, means including a latching device to retain said shaft in ineffective position. 7. In a typewriting machine, in combination, a revolute platen, a carriage therefor having a rearward extension, a carbon-carrier mounted for forward and rearward 30 movement on said extension, and means to prevent cumulative creeping of separate plies fed around said platen, comprising pins mounted on said carrier, so that they may be projected into correspondingly positioned perforations in superposed forms on the separate plies to prevent relative displacement of the forms during the feeding of the plies around the platen, and means for withdrawing said pins simultaneously, comprising a projection on each of the pins, a 35 shaft, arms on said shaft underlying said projections and means to turn said shaft. 8. In a typewriting machine, in combination, a revolute platen, a carriage therefor having a rearward extension, a carbon-carrier mounted for forward and rearward movement on said extension, and means to prevent cumulative creeping of separate plies fed around said platen, comprising pins mounted on said carrier, so that they may be projected into correspondingly positioned perforations in superposed forms on the separate plies to prevent relative displacement of the forms during the feeding of the plies around the platen, and means for withdrawing said pins simultaneously, comprising a projection on each of the pins, a 40 shaft, arms projecting from said shaft and underlying said projections and means to urge said shaft to turn in a direction to withdraw said pins, means including a latching device to retain said shaft in ineffective position, and means controlled by said carbon-carrier for automatically releasing said latching device to permit said shaft to turn and withdraw said pins to ineffective position. 9. In a typewriting machine, in combination, a revolute platen, a carriage therefor having a rearward extension, a carbon-carrier mounted for forward and rearward movement on said extension, means to prevent cumulative creeping of separate plies fed around said platen, comprising pins mounted on said carrier, so that they may be projected into correspondingly positioned perforations in superposed forms on the separate plies during the feeding of the plies around the platen, and means for withdrawing said pins simultaneously, including a member urged in one direction, means whereby movement of said member in said direction will effect the withdrawal of said pins, and movement in the opposite direction will release said pins, and means for latching said member in ineffective position. 10. In a typewriting machine, in combination, a revolute platen, a carriage therefor having a rearward extension, a carbon-carrier mounted for forward and rearward movement on said extension, means to prevent cumulative creeping of separate plies fed around said platen, comprising pins mounted on said carrier, so that they may be projected into correspondingly positioned perforations in superposed forms on the separate plies to prevent relative displacement of the forms during the feeding of the plies around the platen, and means for withdrawing said pins simultaneously, including a member urged in one direction, means whereby movement of said member in said direction will effect the withdrawal of said pins, and movement in the opposite direction will release said pins, and means for latching said member in ineffective position. 11. In a typewriting machine, in combination, a revolute platen, a carriage therefor having a rearward extension, a carbon-carrier mounted for forward and rearward movement on said extension, means to prevent cumulative creeping of separate plies fed around said platen, comprising pins mounted on said carrier, so that they may be projected into correspondingly positioned perforations in superposed forms on the separate plies to prevent relative displacement of the forms during the feeding of the plies around the platen, and means for withdrawing said pins simultaneously, including a member urged in one direction, means whereby movement of said member in said direction will effect the withdrawal of said pins, and movement in the opposite direction will release said pins, and means for latching said member in ineffective position.

separate plies to prevent relative displacement of the forms when the plies are fed around the platen, means for withdrawing said pins simultaneously, including a member urged in one direction, means whereby movement of said member in said direction will effect the withdrawal of said pins, and movement in the opposite direction will release said pins, means for latching said member in ineffective position, and automatic means to release said member from the latching means when the carbon-carrier is moved to a predetermined position.

12. In a typewriting machine, in combination, a revolute platen, a carriage therefor having a rearward extension, a carbon-carrier mounted for forward and rearward movement on said extension, means to prevent cumulative creeping of separate plies fed around said platen, comprising pins mounted on said carrier, so that they may be projected into correspondingly positioned perforations on superposed forms on the separate plies to prevent relative displacement of the forms during the feeding of the plies around the platen, and a support for said plies, on the carrier, having perforations to receive said pins when the latter pass through perforations in said plies.

13. In a typewriting machine, in combination, a revolute platen, a platen-carriage having a rearward extension, a carbon-carrier shiftable on said extension, pins slidably mounted on said carrier and supportable by a plurality of plies passed through said carrier, except when suitably positioned perforations in the plies are brought into register therewith, spring means rendered effective upon the advance of the carrier to a predetermined position to withdraw said pins, and manually-operable means for restoring said spring means to ineffective condition.

14. In a typewriting machine, in combination, a revolute platen, a platen-carriage having a rearward extension, a carbon-carrier, shiftable on said extension, to support carbon sheets interleaved between separate superposed plies, having sets of superposed forms, passing through the carbon-carrier to the platen, and means on said carrier for holding said plies against relative displacement, comprising members controlled by the plies, so that the holding means will be prevented from becoming effective unless the superposed forms on separate plies are in register.

15. In a typewriting machine, in combination, a revolute platen, a platen-carriage having a rearward extension, a carbon-carrier, shiftable on said extension, to support carbon-sheets interleaved between separate superposed plies, having sets of superposed forms and correspondingly positioned perforations, passing through the carbon-car-

rier to the platen, and means on said carrier for holding the superposed plies against relative movement, said means being held in ineffective condition unless said perforations are in register.

16. In a typewriting machine, in combination, a revolute platen, a platen-carriage having a rearward extension, a carbon-carrier, shiftable on said extension, to support carbon-sheets interleaved between separate superposed plies, having sets of superposed forms and correspondingly positioned perforations, passing through the carbon-carrier to the platen, means on said carrier for holding the superposed plies against relative movement, said means being held in ineffective condition unless said perforations are in register, and means to automatically release said plies from said holding means when the carrier is advanced to a predetermined position.

17. In a typewriting machine, in combination, a revolute platen, a platen-carriage having a rearward extension, a carbon-carrier, shiftable on said extension, to support carbon-sheets interleaved between separate superposed plies, having sets of superposed forms and correspondingly positioned perforations, passing through the carbon-carrier to the platen, means on said carrier for holding the superposed plies against relative movement, said means being held in ineffective condition unless said perforations are in register, and spring means rendered effective to release said plies from said holding means when the carrier is advanced to a predetermined position.

18. In a typewriting machine, in combination, a revolute platen, a platen-carriage having a rearward extension, a carbon-carrier, shiftable on said extension, to support carbon-sheets interleaved between separate superposed plies, having sets of superposed forms and correspondingly positioned perforations, passing through the carbon-carrier to the platen, means on said carrier for holding the superposed plies against relative movement, said means being held in ineffective condition unless said perforations are in register, spring means rendered effective to release said plies from said holding means when the carrier is advanced to a predetermined position, and means to restore said spring means to ineffective condition.

19. In a typewriting machine, in combination, a revolute platen, a platen-carriage having a rearward extension, a carbon-carrier shiftable on said extension and having a forwardly-extending arm to facilitate such shifting, web-holding means on the rear of the carbon-carrier, and controlling means for said web-holding means including a movable member, a spring urging said movable member in a direction to render the holding means ineffective, a finger-piece movably mounted on

said arm near its forward end, a link connecting said finger-piece and said member to enable the holding means to be rendered effective, and a latch to hold the member in 5 position when shifted by said finger-piece.

20. In a typewriting machine, in combination, a revoluble platen, a platen-carriage having a rearward extension, a carbon-carrier shiftable on said extension and having 10 a forwardly-extending arm to facilitate such shifting, web-holding means on the rear of the carbon-carrier, and controlling means for said web-holding means including a movable member, a spring urging said mov-

able member in a direction to render the 15 holding means ineffective, a finger-piece movably mounted on said arm near its forward end, a link connecting said finger-piece and said member to enable the holding means to be rendered effective, a latch to hold the 20 member in position when shifted by said finger-piece, and automatic means to withdraw said latch when the carrier is advanced to a predetermined position.
